UNITED STATES PATENT OFFICE.

OVERTON WINSTON, OF MINNEAPOLIS, MINNESOTA.

HEADLIGHT.

1,279,202.

Specification of Letters Patent. Patented Sept. 17, 1918.

Application filed April 17, 1916, Serial No. 91,510. Renewed February 15, 1918. Serial No. 217,460.

To all whom it may concern:

Be it known that I, OVERTON WINSTON, a citizen of the United States, residing at Minneapolis, in the county of Hennepin 5 and State of Minnesota, have invented certain new and useful Improvements in Headlights; and I do hereby declare the following to be a full, clear, and exact description of the invention, such as will enable others 10 skilled in the art to which it appertains to make and use the same.

My present invention relates to headlights for automobiles or other vehicles and is in the nature of an improvement on or modification of the means for adjusting the light bulb thereof, disclosed and claimed in my earlier application S. N. 86,851, filed of date, March 27th, 1916, and entitled "Headlight."

20 Generally stated, the invention consists of the novel construction and combination of parts hereinafter described and defined in the claims.

25 In the accompanying drawings which illustrate the invention, like characters indicate like parts throughout the several views.

Referring to the drawings:

Figure 1 is a vertical section taken centrally through a headlight embodying my invention; and

Fig. 2 is a fragmentary view in front elevation showing parts found in the vicinity of the line marked $\alpha-\alpha$ on Fig. 1.

30 The numeral 1 indicates the case of an ordinary headlight such as used in automobiles, and the numerals 2 and 3 indicate, respectively, the reflector and the lens or glass plate of the headlight. The electric bulb 4 is of well known or any suitable type and is detachably held in a lamp socket, such, for example, as that illustrated in my prior application above identified, and which lamp socket is indicated, as an en- 45 tirety, by the numeral 5.

The lamp socket 5 is intermediately pivoted at 6 to a hollow supporting head 7 that is provided with a threaded shank screwed into an annular anchoring plate 8 50 that is rigidly secured to the back of the reflector 2 and surrounds an axial passage 2^a in the latter. The passage 2^a affords clearance for the front end of the lamp socket.

55 For oscillating the lamp socket vertically,

I provide upper and lower electro-magnets 9, both of which are rigidly secured to and carried by the hollow bearing head 7. As shown, the said head 7 is provided with projecting flanges 7^a to which the said electro-magnets 9 are directly secured. At their inner extremities, the electro-magnets 9 are provided with pole pieces 9^a and at their outer extremities, with pole pieces 9^b. The pole pieces 9^a act upon and limit the oscillatory movements of the rear metallic sleeve portion of the lamp socket 5.

Small upper and lower lock levers 10 are intermediately pivoted to the flanges 7^a and are provided at their inner ends with lock 70 heads 11. The outer ends of said levers 10 are yieldingly pressed rearward by light springs 12, shown as anchored to the flanges 7^a. The outer ends of the levers 10 serve as armatures that are adapted to be re- 75 tracted by the outer pole pieces 9^b of the respective electro-magnets.

The operation of the lamp socket, electro-magnets and latches, is the same as disclosed in my above identified prior applica- 80 tion, and hence, for the purposes of this case, it is only desirable to state that when the upper electro-magnet is energized, it will draw upward the rear end of the lamp socket so as to move the lamp downward to 85 a point where its filament will be at the axis of the reflector, and in this position, the socket will be locked by the lower latch lever. The release of the upper latch lever is, of course, accomplished before the socket 90 can move. In the raised position of the light bulb shown by full lines in Fig. 1, the upper latch lever holds the rear end of the lamp socket downward. It will, of course, be understood that when the lower electro- 95 magnet is energized, the lower latch lever will be first released and then the rear end of the lamp socket will be drawn downward, as shown by full lines in Fig. 1.

In the said prior application, no positive 100 devices were shown either for holding the supporting head 7 against rotation, or for supporting the same from the lamp casing, as well as from the reflector. The present invention is directed to means for accomplishing 105 these two results, and it is preferably accomplished as follows: The lamp casing is provided with rigidly secured vertically spaced and vertically aligned anchoring flanges 13 having approximately parallel edges that are 110

arranged to engage grooves 14 in the outer faces of the outer pole pieces 9^b. Preferably, also, the slot engaging edge of one of the anchoring flanges 13 is faced with a leaf spring 15 which will take up slack and prevent rattling, if there happens to be play between the two anchoring flanges and the engaging pole pieces of the electro-magnets.

In assembling the parts of the device, the 10 threaded shank of the supporting head 7, would preferably be first screwed into the annular anchoring plate 8 on the back of the reflector, while the reflector, of course, is removed from the casing. Then the reflector 15 will be placed in proper position, in respect to the casing by a rearward movement with the grooves 14 of the pole pieces 9^b engaged with the parallel edges of the anchoring flanges 13, and the electro-magnets thereby slid back to final position 20 shown in Fig. 1. When the said parts are thus positioned, the so-called anchoring flanges 13 positively lock the head 7 against rotation, and afford a solid supporting connection between the electro-magnets and the 25 casing. In this way, the lamp socket support and the electro-magnets are held against vibration and afford a base connection between the reflector and casing.

30 What I claim is:

1. In a headlight, the combination with a casing and a reflector therein, of a socket support connected to the back of said reflector by screw-threaded engagement, parts 35 of said socket support and casing having interlocking engagement, and a lamp socket mounted on said socket support in position to support an electric light bulb within the said reflector.

40 2. In a headlight, the combination with a casing and a reflector, of a socket support connected to said reflector by screw-threaded engagement, a lamp socket pivoted to said socket support and electro-magnetic means 45 for oscillating the socket, and an interlocking connection between said socket support and casing holding said socket support against rotation.

3. In a headlight, the combination with 50 a casing and a reflector removably mounted therein, of a socket support connected to said reflector by screw-threaded engagement, a lamp socket pivoted to said socket support, an electro-magnet on said socket support, 55 for operating said lamp socket, an anchoring flange on the interior of said casing, and an interlocking sliding connection be-

tween said electro-magnet and anchoring flange.

4. In a headlight, the combination with 60 a casing and a reflector removably mounted therein, of a socket support connected to said reflector by screw-threaded engagement, a lamp socket pivoted to said socket support, upper and lower electro-magnets 65 for operating said socket, and upper and lower anchoring flanges on the interior of said casing, said electro-magnets at their outer extremities having interlocking sliding engagement with said anchoring flanges. 70

5. In a headlight, the combination with 75 a casing and a reflector removably mounted therein, of a socket support connected to said reflector by screw-threaded engagement, a lamp socket pivoted to said socket support, upper and lower electro-magnets for operating said socket, and upper and lower anchoring flanges on the interior of said casing, said electro-magnets at their outer extremities having interlocking sliding engagement with said anchoring flanges, 80 one of said anchoring flanges having its magnet engaging edge faced with a leaf spring to take up play.

6. In a headlight, the combination with 85 a casing and a reflector removably mounted therein, of a socket support connected to said reflector by screw-threaded engagement, a lamp socket pivoted to said socket support, upper and lower electro-magnets 90 secured to said socket support and operative on said socket, said magnets having inner and outer end pole pieces, the latter having locked grooves, upper and lower latches pivoted to said socket support and 95 subject to the outer end pole pieces of said electro-magnets, and upper and lower anchoring flanges on the interior of said casing, said flanges having approximately parallel edges that are engageable with the 100 grooves in said outer end pole pieces.

7. In a headlight, the combination with 105 a casing and a reflector removably mounted therein, of a socket support primarily supported by said reflector, and anchoring flanges on the interior of said casing having sliding interlocking engagement with parts carried by said socket support.

In testimony whereof I affix my signature in presence of two witnesses.

OVERTON WINSTON.
